 Steglitz, Germany

Application August 6, 1937, Serial No. 157,721
 In Germany August 8, 1936

5 Claims. (Cl. 178—7.6)

It is well known in the television are to use scanning discs having a multiple spiral of apertures or lenses and to clear the single turns one after the other by means of an interceptor having one spiral aperture and rotating at a correspondingly lower speed. By practical reasons it is impossible to arrange both discs closed together, so that the shadow of one disc onto the other is not very sharp. It has also been proposed to project the scanning disc by an objective sharply onto the interceptor, i. e. to arrange both in subsequent image planes of the optic system. In this arrangement the full light of the light source was projected onto the scanning disc, thus heating the latter in a troublesome degree, particularly if it is running in the vacuum. Also by other reasons this arrangement has disadvantages.

According to the invention both discs are also arranged in subsequent image planes of the optic system, but so that the light ray passes the scanning disc after the interceptor.

The invention will fully appear from the following description in which reference will be made to the accompanying drawings in which

Fig. 1 shows diagrammatically the optic arrangement,

Fig. 2 an interceptor according to the invention,

Fig. 3 a modification of the arrangement of Fig. 1.

It is supposed that the apparatus is provided with a device correcting in a known manner the keystone effect produced by the use of spirally apertured scanning discs by inclining the shaft of the scanning disc towards the optic axis by an angle α .

In Fig. 1, 1 is an arc lamp, which by way of a concave reflector 2 and a condenser 3 lights a peculiarly formed conical intercepting disc 4. The intercepting disc 4 is driven by the motor 5 and is by means of the objectives 6 and 7 reproduced onto the scanning disc 8 driven by the synchronous motor 9 with 2 to 4 times the circumferential velocity of 5. The scanning disc 8 is projected by the objectives 10 and 11 onto the inclined plane of the film 12 to be transmitted. After it the photo-cell (not shown) is placed.

As the shaft of the disc has to be inclined towards the optic axis by the said angle α and, on the other hand by mechanical reasons is horizontal, the optic axis must be inclined towards the horizontal by the angle α . The operating part of the surface of the interceptor has to be vertical towards the optical axis. Instead to give

the shaft of the interceptor 4 a corresponding inclination the disc is replaced by a conical wheel of the corresponding aperture angle stiffened by the border 41. The conical part 42 is provided with the spiral aperture 43. The form of the latter is better to be recognized in Fig. 2. The spiral is interrupted by two spokes 14, 15 supporting the border. Its pitch corresponds to the total radial width of the multiple spiral of the scanning disc.

A fixed diaphragm 19 having an opening 23 defining the size of the frame may be arranged closed to the interceptor 4 before or after it.

The interceptor may also be used for the generation of the frame synchronising impulses. For this purpose outside of the spiral 43 (Fig. 2) two circumferential slots 20a and 20b are provided. The light passing through them is conducted, e. g. by a prism 44 (Fig. 1), to a special photo-cell 45 or even to the image photo-cell. Thus at each turn of the interceptor two synchronising impulses are generated. In order to adjust the intensity of these impulses and to bring it in accordance with the video signals a fine gap 24 adjustable by means of a screen 22 may be provided on the diaphragm 19.

It has been found to be particularly convenient to break the comparatively long way of the light by means of a mirror. Fig. 3 shows the arrangement then resulting, which can be accommodated within a very small space. Motor 9, scanning disc 8, reproducing objectives 10 and 11, film 12 and machine 18 operating it are arranged on a table 17. Below the table 17 there is arranged the light source 1 with reflector 2, the interceptor 4, the objectives 6 and 7 and the vertical mirror 16.

The interceptor is here e. g. mounted on a vertical shaft; consequently a cone 4 having a more acute angle is to be used.

I claim:

1. In a television transmitter a scanning arrangement comprising a source of light, a light beam concentrating device, a rotating interceptor diaphragm, a scanning disc having a spiral of apertures of more than one turn, a film to be scanned and two optical systems for projecting the plane of said interceptor on said disc and of said disc on the film, respectively, said interceptor having a conical border being provided with a spiral aperture of one turn for uncovering alternately one of said disc spiral turns, the shaft of said disc and that of said interceptor being horizontal.

2. In a television transmitter a scanning ar-

5 arrangement comprising a source of light, a light beam concentrating device, a rotating interceptor diaphragm, a scanning disc having a spiral of apertures of more than one turn, a film to be scanned and two optical systems for projecting the plane of said interceptor on said disc and of said disc on the film, respectively, said interceptor having a conical border being provided with a spiral aperture of one turn for uncovering alternately one of said disc spiral turns, the shaft of said disc and that of said interceptor being horizontal, said interceptor being arranged between light source and scanning disc.

10 3. In a television transmitter a scanning ar-
15 arrangement comprising a source of light, a light beam concentrating device, a rotating interceptor diaphragm, a scanning disc having a spiral of apertures of more than one turn, a film to be scanned and two optical systems for projecting the plane of said interceptor on said disc and of said disc on the film, respectively, said interceptor having a vertical shaft and a conical portion being provided with a spiral aperture of one turn for uncovering alternately one of said disc spiral turns, the shaft of said disc being horizontal.

15 5. In a television transmitter a scanning ar-
20 arrangement comprising a source of light, a light beam concentrating device, a rotating interceptor diaphragm, a scanning disc having a spiral of apertures of more than one turn, a film to be scanned and two optical systems for projecting the plane of said interceptor on said disc and of said disc on the film, respectively, said interceptor having a vertical shaft and a conical portion being provided with a spiral aperture of one turn for uncovering alternately one of said disc spiral turns, the shaft of said disc being horizontal.

25 3. In a television transmitter a scanning ar-
30 arrangement comprising a source of light, a light beam concentrating device, a rotating interceptor diaphragm, a scanning disc having a spiral of apertures of more than one turn, a film to be scanned and two optical systems for projecting the plane of said interceptor on said disc and of said disc on the film, respectively, said interceptor having a vertical shaft and a conical portion being provided with a spiral aperture of one turn for uncovering alternately one of said disc spiral turns, the shaft of said disc being horizontal.

4. In a television transmitter a scanning ar-

5 arrangement comprising a source of light, a light beam concentrating device, a rotating interceptor diaphragm, a scanning disc having a spiral of apertures of more than one turn, a film to be scanned and two optical systems for projecting the plane of said interceptor on said disc and of said disc on the film, respectively, said interceptor having a vertical shaft and a conical portion being provided with a spiral aperture of one turn for uncovering alternately one of said disc spiral turns, the shaft of said disc being horizontal.

10 5. In a television transmitter a scanning ar-
15 arrangement comprising a source of light, a light beam concentrating device, a rotating interceptor diaphragm, a scanning disc having a spiral of apertures of more than one turn, a film to be scanned and two optical systems for projecting the plane of said interceptor on said disc and of said disc on the film, respectively, said interceptor having a vertical shaft and a conical portion being provided with a spiral aperture of one turn for uncovering alternately one of said disc spiral turns, the shaft of said disc being horizontal.

20 5. In a television transmitter a scanning ar-
25 arrangement comprising a source of light, a light beam concentrating device, a rotating interceptor diaphragm, a scanning disc having a spiral of apertures of more than one turn, a film to be scanned and two optical systems for projecting the plane of said interceptor on said disc and of said disc on the film, respectively, said interceptor having a vertical shaft and a conical portion being provided with a spiral aperture of one turn for uncovering alternately one of said disc spiral turns, the shaft of said disc being horizontal.

30 KURT SCHLESINGER.
